PROCESS OF PRODUCING FAST DYEINGS ON
VULCANIZED FIBER AND THE DYED FIBER
OBTAINED THEREBY

tion, a corporation of Delaware

No Drawing. Application October 14, 1939, Serial
No. 299,572. In Germany October 10, 1938

6 Claims. (Cl. 8—7)

The present invention relates to a process of producing fast dyeings on vulcanized fiber and to the dyed fiber obtained thereby.

Colored vulcanized fiber has hitherto been prepared by parchmentizing webs of colored paper or fabrics. The process has the drawback that it is limited to such dyestuffs as are not destroyed by the parchmenting process that is to say only brown to black shades which are prepared by the use of iron oxide or soot can be obtained. The application of organic dyestuffs entails great difficulty since they are destroyed to a large extent by the parchmenting process. By dyeing the plates, sheets or shaped bodies of vulcanized fiber with the substantive or acid dyestuffs usually applied in paper dyeing there have been obtained hitherto only dyeings whose fastness to water and to rubbing do not comply with the requirements of practice. In most cases only the surface of the material is dyed so that, when 20 the material is broken, bent or punched or when its surface is destroyed mechanically, the undyed fiber appears.

Now, we have found that finished vulcanized fiber may be dyed throughout or in the grain various tints, by treating sheets, plates or finished articles made from vulcanized fiber with leuco-esters of vat-dyestuffs and producing the vat dyestuff in and on the fiber in known manner by splitting off the ester groups and oxidizing.

The dyeings thus obtained are distinguished by a very good fastness to water and to rubbing as well as to light.

The following examples serve to illustrate the invention, but they are not intended to limit it thereto:

1. Bleached vulcanized fiber of 0.5 mm. thickness is treated at 70° C. for 2 hours in a bath containing per liter 5 grams of the sodium salt of the sulfuric acid ester of the vat dyestuff having the following formula:

3 cc. of ammonia of 25 per cent strength and 5

grams of sodium nitrite. The vulcanized fiber is then introduced into a bath containing 25 cc. of concentrated sulfuric acid per liter of cold water and treated in this bath for 1-2 hours.

5 It is then well rinsed and dried.

A pink vulcanized fiber is thus obtained which has been dyed throughout and has a very good fastness to water and to light.

2. Bleached vulcanized fiber of 0.5 mm. thickness is treated at 70° C. for 2 hours in a bath containing per liter 2 grams of the sulfuric acid ester of the vat-dyestuff having the following formula:

15

and 2 grams of the sulfuric acid ester of dichloro - N - dihydro - 1,2,1',2' - anthraquinone-azine (Schultz Farbstofftabellen, 1931, No. 1234) 25 in the form of their sodium salts, 3 cc. of ammonia of 25 per cent strength and 5 grams of sodium nitrite. The vulcanized fiber is then introduced into a bath containing per liter 25 cc. of concentrated sulfuric acid and treated in this bath for 1-2 hours. The material is then rinsed and dried.

A green vulcanized fiber is thus obtained which has been dyed throughout and has very good properties of fastness.

3. Tubes made from vulcanized fiber are treated at 70° C. for one or several hours, according to the thickness of their walls, in a bath containing per liter 4 grams of the sulfuric acid ester sodium salt of dichloro-N-dihydro-1,2,1',2'-anthraquinone-azine (Schultz Farbstofftabellen, 1931, No. 1234), 5 cc. of ammonia and 5 grams of sodium nitrite. The material is then treated at room temperature for several hours with a solution of 25 cc. of concentrated sulfuric acid per liter of water, rinsed and dried.

The dyeing obtained is a vivid blue. According to the duration of the dyeing operation and development the material is dyed to various depths of penetration. By developing with sulfuric acid

at raised temperature, somewhat more green dyeings are obtained.

4. By using in Example 1 instead of the leuco-ester 4 grams of the sodium salt of the leuco-ester of the dyestuff having the following formula:

a green shade is obtained.

We claim:

1. Process of producing fast dyeings on vulcanized fiber which comprises applying to the finished vulcanized fiber leuco-esters of vat dyestuffs and producing the vat dyestuff in and on the fiber by splitting off the ester groups and oxidizing.

2. Process of producing fast blue dyeings on vulcanized fiber which comprises applying to the finished vulcanized fiber the sulfuric acid ester sodium salt of dichloro-N-dihydro-1,2,1',2'-anthraquinone-azine and producing the vat dyestuff in and on the fiber by splitting off the ester groups and oxidizing.

3. Process of producing fast green dyeings on vulcanized fiber which comprises applying to the finished vulcanized fiber the sodium salt of the leuco-ester of the dyestuff having the following formula:

10

15 and producing the vat dyestuff in and on the fiber by splitting off the ester groups and oxidizing.

4. Vulcanized fiber dyed with a vat dyestuff obtained on the fiber by the process claimed in claim 1.

5. Vulcanized fiber dyed with a vat dyestuff obtained on the fiber by the process claimed in claim 2.

25 6. Vulcanized fiber dyed with a vat dyestuff obtained on the fiber by the process claimed in claim 3.
